[57] CLAIM

The ornamental design for the combined utensil holder and fork therefor, as shown and described.

DESCRIPTION

FIG. 1 is a top plan view of a combined utensil holder and forks therefor showing my new design;

FIG. 2 is a front elevation view thereof, the other sides being a mirror image;

FIG. 3 is a bottom plan view thereof;

FIG. 4 is a top plan view of the fork;

FIG. 5 is a right side elevation view of FIG. 4, the opposite side being a mirror image;

FIG. 6 is a front elevation view of FIG. 4, the opposite side being a mirror image; and,

FIG. 7 is a bottom plan view thereof.

The broken lines are for illustrative purposes only and form no part of the claimed design. The fork is shown separately for clarity of illustration.
